UNITED STATES PATENT OFFICE.

CHESTER M. POETSCH, OF CHICAGO, ILLINOIS.

RADIATOR-COVER AND HUMIDIFIER.

1,284,765.

Specification of Letters Patent. Patented Nov. 12, 1918.

Application filed May 5, 1917. Serial No. 166,559.

To all whom it may concern:

Be it known that I, CHESTER M. POETSCH, a citizen of the United States, residing at Chicago, in the county of Cook and State of Illinois, have invented a new and useful 5 Radiator-Cover and Humidifier, of which the following is a specification.

The objects of my invention are to provide a shield for inclosing steam radiators, particularly the back and top, which will be simple and attractive in appearance, durable and economical in construction, and having a removable top piece so that the radiator when inclosed with my shield may 10 be used as a window-seat, shelf or the like.

A further object is a combination of parts in my radiator shield so that they may be finished to conform to the woodwork, decorations and furnishings of a room as to color 15 and character of finish.

Another object of my invention is to provide, in combination with my shield, means for storing water so as to secure and maintain the desired per cent. of humidity with- 20 in the room.

A further object of my invention is to secure the combination of parts in such a manner as to reduce the heat on the shelf top by means of the water supply stored un- 25 derneath same so as to secure the complete use of the top for the purposes of a window seat, shelf or the like.

Still further objects of my invention consist in the arrangement of a radiator shield 30 so as to keep both heat and dust away from the wall adjacent to the radiator, thus preventing discoloration, cracking, etc.

Another object of my invention is to provide a combination radiator shield and humidifier consisting of few and simple parts 35 easily assembled and disassembled, having roller bearings for the shelf top so that it may be easily displaced in order to renew the water supply and so that the water reservoir and top of the radiator may be accessible 40 for cleaning or any other purpose. The roller bearings for the top permit it to be easily displaced or replaced regardless of the length or weight of the seat top.

The special and novel advantages of my invention herein disclosed may be better understood by reference to the following detailed description which is to be taken in conjunction with the accompanying drawings 50 wherein Figure 1 is a perspective view of a device embodying my invention in place

upon the radiator, showing the top displaced and the water pan exposed to view. Fig. 2 is a transverse section of Fig. 1. Fig. 3 is a view of a portion of the radiator with 60 a longitudinal sectional view of the water reservoir. Fig. 4 is a reservoir supported on the top of the radiator and not in any wise supported by or engaging the back member. Fig. 5 is a view of the various parts in an 65 unassembled state.

In carrying out my invention I first provide the back member 10 which may or may not extend to the floor as desired. For stiffening the edges of this back member it may 70 be crimped or bent so as to secure additional thickness and strength as shown at 11 and 12. I next provide the end members 13 which, because exposed to view, may be of any ornamentation or design desired. 75 These end members 13 may be connected with the back member 10 by any suitable means such as rivets or bolts. Each of the end members 13 have a member 14 which extends inwardly over the top of the radiator, 80 which in turn is tied to the radiator by means of the holder 15. This holder 15 may be of any suitable material and is drawn to desired tightness about the radiator by means of a screw bolt 16 or any other suitable means. This connection is best shown in Fig. 2. I connect the end members at the front by means of a T-iron 17. The inner flange 18 of this T-iron 17 serves as a support for the water reservoir when made in full 85 width. The outer flange 19 of this T-iron 17 forms the lower line of an aperture through which the moisture laden air escapes into the room. The T-iron 17 is secured to the end members 13 by any suitable 90 means such as bolts 20. I next provide a water reservoir 21 which may be made in a great variety of sizes and shapes, having capacity to suit the requirements of the room and radiation.

In Fig. 2 the water reservoir is shown occupying the entire space between the back member 10 and the T-iron 17 resting at the front on the flange 18 of the T-iron 17 and supported on the back member 10 as shown 100 at 22. When made in this manner, the reservoir 21 is supported by the back member 10 and the T-iron 17. When this form of water reservoir is used, I have provided at the back thereof a plurality of holes 23 shown 105 in Figs. 1 and 3, to permit the air coming up between the back member 10 and the

back of the radiator to pass through these holes over the surface of the water in the reservoir and out into the room bearing the moisture thus received from the water in the 5 reservoir.

In Fig. 4 I have shown another style of water reservoir which I have made of less width and not supported by or connected with the back member 10. When this type 10 of reservoir is used, it may be supported by the radiator and the flange 18 of the T-iron 17, or alone by the radiator, or by projections from members 13. This will permit the air to come up between the back member 15 10 and the back of the radiator and pass over the water in the reservoir thereby securing the moisture laden air as desired. A great variety of reservoirs may in this way be provided, the object sought being to provide 20 a reservoir of sufficient capacity and open surface so that the air passing through and over will secure the desired amount of moisture. If desired, the bottom of the reservoir 25 25 may be provided with an asbestos lining 24 or other suitable lining to prevent an undue heating of the water in the reservoir.

I next provide a top 25 which should be of material of sufficient strength to permit 30 it to fulfil the function of a seat, shelf or the like. This top member when in position rests on lugs 26 of the end members 13 and when in place the top member is flush with the top of the end members so that a smooth 35 surface is exposed. The sides of the top member are flanged downwardly. The back flange 27 is guided in a stirrup 28 and rides on the member 10 and projecting lugs 26 of members 13 when the top is drawn open 40 for refilling or cleaning, when the type of reservoir shown in Fig. 2 is used.

Another stirrup 29 is provided on the back member 10 when a reservoir like that shown in Fig. 4 is used. The back member 10 may 45 be provided with a continuous stirrup 29 or a plurality of separate stirrups. The front flange 30 of the top 25 extends downwardly toward the front flange 19 of the T-iron 17 forming an aperture 31 through which the 50 moisture laden air escapes into the room.

It will be seen that my combination radiator shield and humidifier can be made in standard sizes, styles and designs in great variation without departing from the spirit 55 of my invention; that the size, shape, material, etc., of the various parts in no wise modify the principle of my combination.

While I have herein disclosed one embodiment of my invention, I desire that the protection herein sought include such changes 60 and modifications in detail as reasonably may be made within the terms of the appended claims.

Having fully described my invention, what I claim and desire to secure by Letters 65 Patent is:

1. The combination with a radiator of a frame having back, front and side members secured together with suitable connections, said front member being provided with an 70 inwardly extending flange, means such as lugs 14 and straps 15 for securing the frame to the radiator, a removable top, a moisture reservoir, with a series of openings 23, extending over the entire radiator top and supported by the lugs 14 and said inwardly extending flange of the front member and having a flange at the top and back thereof which fits over and rests on the back member. 75

2. The combination with a radiator of a frame having back, front and side members secured together with suitable connections, means such as lugs 14 and straps 15 for securing the frame to the radiator, a removable top, a moisture reservoir, with a series of openings 23, extending over the entire radiator top and supported thereon and having a flange at the top and back thereof which fits over and rests on the back member. 80

3. The combination with a radiator of a frame having back, front and side members secured together with suitable connections, said front member being provided with an inwardly extending flange, means such as lugs 14 and straps 15 for securing the frame to the radiator, a removable top, and a moisture reservoir supported by the lugs 14 and said inwardly extending flange of the front member. 85

4. The combination with a radiator of a frame having back, front and side members secured together with suitable connections, means such as lugs 14 and straps 15 for securing the frame to the radiator, a removable top, and a moisture reservoir, with a series of openings 23, supported by the lugs 14 and having a flange at the top and back thereof which fits over and rests on the back member. 90

In witness whereof, I hereunto subscribe my name to this specification.

CHESTER M. POETSCH.
